(57) **CLAIM**

The ornamental design for an elastic textile, as shown and described.

DESCRIPTION

FIG. 1 is a perspective view of an elastic textile showing my new design;

FIG. 2 is a top plan view thereof;

FIG. 3 is a bottom plan view thereof;

FIG. 4 is a front elevational view thereof shown in cross section taken along lines 4-4 of FIG. 2;

FIG. 5 is a rear elevational view thereof shown in cross section taken along lines 5-5 of FIG. 2;

FIG. 6 is a left side elevational view thereof shown in cross section taken along lines 6-6 of FIG. 2;

FIG. 7 is a right side elevational view thereof shown in cross section taken along lines 7-7 of FIG. 2;

FIG. 8 is a perspective view of an elastic textile showing my new design in accordance with an embodiment;

FIG. 9 is a top view thereof;

FIG. 10 is a bottom plan view thereof;

FIG. 11 is a front elevational view thereof shown in cross section taken along lines 11-11 of FIG. 9;

FIG. 12 is a rear elevational view thereof shown in cross section taken along lines 12-12 of FIG. 9;

FIG. 13 is a left side elevational view thereof shown in cross section taken along lines 13-13 of FIG. 9; and,

FIG. 14 is a right side elevational view thereof shown in cross section taken along lines 14-14 of FIG. 9.

In the figures, the bold broken lines surrounding the perimeter define the bounds of the claimed design and form no part thereof. In addition, the further broken line illustration of environmental structure in the Figures is not part of the claimed design. Further, the claimed design is directed to the features within the solid lines in the Figures, and all surfaces outside of the solid lines form no part of the claimed design.
